US0D1034861S

(12) **United States Design Patent** (10) **Patent No.:** **US D1,034,861 S**
(45) **Date of Patent:** **** Jul. 9, 2024**

(54) **TOY WATER BALL**

(71) Applicant: **Dongguan Sainchuangke Technology Co., Ltd**, Dongguan (CN)

(72) Inventors: **Yunfeng Chen**, Dongguan (CN); **Lixiang Liao**, Dongguan (CN)

(73) Assignee: **DONGGUAN SAIENCHUANGKE TECHNOLOGY CO., LTD**, Dongguan (CN)

(**) Term: **15 Years**

(21) Appl. No.: **29/929,607**

(22) Filed: **Feb. 22, 2024**

Related U.S. Application Data

(63) Continuation-in-part of application No. 29/879,617, filed on Jul. 11, 2023, and a continuation-in-part of application No. 17/549,920, filed on Dec. 14, 2021.

(30) **Foreign Application Priority Data**

Nov. 21, 2023 (CN) 202323145630.1

(57) **CLAIM**

The ornamental design for a toy water ball, as shown and described.

DESCRIPTION

FIG. 1 is a perspective view of a toy water ball in a closed state in accordance with a first embodiment of our new design;

FIG. 2 is another perspective view thereof, showing the toy water ball in an open state;

FIG. 3 is a perspective view of a toy water ball in a closed state in accordance with a second embodiment of our new design; and,

FIG. 4 is another perspective view thereof, showing the toy water ball in an open state.

The broken lines in the drawings depict portions of the toy water ball that form no part of the claimed design.
